DESIGN FOR A MUSTARD-SPOON.

No. 39,250.

Specification for Design.

Patented April 7, 1908.

Application filed February 6, 1908. Serial No. 414,654. Term of patent 14 years.

To all whom it may concern:

Be it known that I, SIMON H. M. SEIB, a citizen of the United States, residing at Jersey City, in the county of Hudson and State of New Jersey, have invented a new, original, and ornamental Design for a Mustard-Spoon, of which the following is a specification, reference being had to the accompanying drawing, forming part thereof.

The figures of the said drawing clearly show my new, original, ornamental design; and in the said drawings, Figure 1 is a top view, Fig. 2 a bottom view and Fig. 3 a side view of the mustard spoon, and showing my new original and ornamental design.

I claim:—

The ornamental design for a mustard spoon as shown.

SIMON H. M. SEIB.
